UNITED STATES PATENT OFFICE.

LESTER A. GILLETT, OF LEONARDVILLE, KANSAS.

AUTOMATIC GRAIN-METER.

SPECIFICATION forming part of Letters Patent No. 424,972, dated April 8, 1890.

Application filed May 18, 1889. Serial No. 311,257. (No model.)

To all whom it may concern:

Be it known that I, LESTER A. GILLETT, a citizen of the United States, residing at Leonardville, in the county of Riley and State of 5 Kansas, have invented a new and useful Automatic Grain-Weigher, of which the following is a specification.

This invention relates to that class of automatic grain-meters which are provided with 10 an oscillating door-plate and with an oscillating bottom at its lower or discharge end, and with a weighted lever forming an extension of the pivoted rod, to which the oscillating bottom is attached; and the invention consists in certain improvements in the construction 15 of the device, which will be hereinafter fully described, and particularly pointed out in the claim.

In the drawings, Figure 1 is a side view of 20 my improved grain-meter. Fig. 2 is a vertical transverse section of the same. Fig. 3 is a perspective view, on a larger scale, of the registering apparatus. Fig. 4 is a sectional view of the latter.

25 The same letters and numerals refer to the same parts in all the figures.

A designates the casing of my improved grain-meter, which is contracted at its upper end, so as to form the neck B, having the 30 mouth or opening C. Journaled in the sides D D of the casing, just below the neck B, is a shaft E, which carries the oscillating door-plate F, and below the said shaft is arranged a vertical partition G, extending to a point 35 not far from the bottom. The oscillating door F may be thrown to either side, so as to rest upon either of the inclined sides H H' of the neck, and thus cut off communication with one of the sides of the casing, while connection is established between the mouth or 40 opening C and the other side of said casing. In the sides of the casing, below the partition G, is journaled another transverse shaft I, carrying two wings J J', which are placed at 45 an angle to each other, and which together constitute the bottom of the meter. The lower end of the casing is curved concentrically with the shaft I, and it has the discharge-opening K, which is of a width equal to the 50 distance between the lower edges of the plates constituting the bottom. The shafts E and I are extended slightly on one side of the eas-

ing, and are provided with pulleys L M, connected by a belt or band N, by means of which motion is communicated from one of said pulleys to the other. The other end of the lower shaft I is likewise extended on the opposite side of the casing, and has an arm or lever O at right angles thereto and carries at its free end an adjustable weight P. Stops Q Q extend from one of the sides D of the casing on opposite sides of the bearing of the shaft I, and serve to support the weighted arm or lever O when the latter is thrown to either side.

R designates the registering apparatus, which comprises three wheels 1, 2, and 3, mounted upon an axle 4, and each provided along its periphery with a series of ten teeth or ratchets, numbered from 0 to 9. The front 70 wheel 1 is the smallest, the teeth or ratchets of the second wheel 1 2 projecting beyond its periphery, and the teeth or ratchets of the third wheel 3 project beyond the periphery of the second. The first wheel 1 is provided 75 on its inner side with a rim or flange 12, which extends to the periphery of the wheel 2, and the latter is provided on its inner side with a flange 13, extending to the periphery of the wheel 3. The flanges 12 and 13 are 80 provided with notches 14, corresponding in position with the zero-notches of the said wheels, of which 1 is the units, 2 the tens, and 3 the hundreds, wheel. Pivoted to an arm or extension 5 of the shaft I, opposite to the 85 arm or lever O, are three pawls 6, 7, and 8, which engage the ratchets of the registering-wheels, the pawl 6 being constantly in engagement with the teeth or ratchets of the wheel 1, while the pawls 7 and 8 ride upon 90 the flanges 12 and 13, respectively, and only come in contact with the ratchets of the wheels 2 and 3 once during each revolution of the wheels 1 and 2, respectively, when the notches 14 of the flanges 12 and 13 of the said 95 wheels come in juxtaposition with the levers or pawls 7 and 8, respectively. One or more of the registering-wheels will thus, as will be hereinafter described, be operated for the space of one notch for each oscillation of the 100 shaft I.

The operation of my invention is as follows: Before starting, the wheels of the register are adjusted with their zero-notches registering

with each other and with the pawl 6 adjusted in the first notch of the units-wheel. The weighted arm or lever O rests upon one of the studs or projections Q, and when it is in 5 this position both of the wings or plates constituting the bottom of the grain-meter are swung to one side of the discharge-opening, while the oscillating door or cut-off F covers the upper end of the compartment on the 10 opposite side of the casing. Suitable spouts are to be arranged to feed the grain into and to carry it away from the meter. It will be seen that when the cut-off plate F is so arranged as to cover the compartment C² the bottom is 15 swung under the compartment C³, into which latter the grain will thus be fed until the weight of the grain in the compartment C³ overbalances the weight P at the outer end of lever O. The latter will not be swung or tilted, 20 thus oscillating the shaft I and reversing the position of the bottom J J', which now swings under the compartment C³, while at the same time the cut-off plate F is reversed and caused to cover the compartment C³. The 25 contents of the compartment H now escape at the bottom, while grain enters the compartment C² at the top until the weight of grain in said compartment overbalances the weight D, when the operation is repeated. At each 30 operation of the lever O the pawl 6, pivoted to the extension 5 of said lever, engages the teeth of the units-wheel of the register and serves to rotate the said wheel for the space of one notch, thus indicating upon the register 35 the number of times the operation has been repeated. When the units-wheel has made one complete revolution, the notch 14 of its flange 12 will come in juxtaposition with the pawl 7, which has meanwhile been riding 40 upon the said flange, and the tens-wheel will thus, by the action of said pawl, be turned forward the space of one notch. This will be repeated at each complete revolution of the units-wheel until the tens-wheel has made 45 one complete revolution, when the pawl 8, which has meanwhile been riding upon the flange 13 of the tens-wheel, will engage the

ratchets of the hundreds-wheel and turn the latter forward the space of one notch, which operation is repeated only at each complete 50 revolution of the tens-wheel. It will thus be seen that the register will at any time indicate the exact number of times that the meter has been operated. The weight of grain required to overbalance the weight T being 55 known, the quantity of grain passing through the meter may be easily computed.

This registering device, it will be seen, is exceedingly simple in construction, being entirely free from complicated mechanism, 60 which is always more or less liable to get out of order and to interfere with the successful operation, and it cannot fail to operate with certainty and accuracy. The meter itself is likewise exceedingly simple, and the cut-off 65 plate at the top and the bottom valve will be operated instantaneously and at the same time.

Having thus described my invention, I claim—

In a grain-meter, the combination of the casing having the contracted neck or upper portion and segmental lower end provided with a discharge-opening, the transverse shafts, the vertical partition extending between said shafts, the cut-off plate upon the upper shaft, the bottom valve upon the lower shaft, comprising two wings or plates, the lower edges of which are a distance apart equal to the width of the discharge opening, 75 80 a weighted arm or lever extending from the lower shaft, studs or projections to support said weighted lever, and a belt or band connecting pulleys upon the two shafts, all arranged and operating substantially as set forth.

In testimony that I claim the foregoing as my own I have hereto affixed my signature in presence of two witnesses.

LESTER A. GILLETT.
